UNITED STATES PATENT OFFICE.

FERDINAND WOLTER, OF GAYLORD, MINNESOTA.

TYPE-WRITING MACHINE.

SPECIFICATION forming part of Letters Patent No. 555,594, dated March 3, 1896.

Application filed March 28, 1893. Serial No. 467,944. (No model.)

To all whom it may concern:

Be it known that I, FERDINAND WOLTER, a citizen of the United States, residing at Gaylord, in the county of Sibley and State of Minnesota, have invented certain new and useful Improvements in Type-Writing Machines; and I do hereby declare the following to be a full, clear, and exact description of the invention, such as will enable others skilled

10 in the art to which it appertains to make and use the same.

My invention relates to type-writing and similar machines which produce impressions from individual type or dies brought in succession to a common printing-point, and has for its object to provide certain improvements in the details of the mechanism with the view of producing a more efficient machine.

To these ends the invention consists in certain novel devices and combinations of devices, which will be hereinafter fully described and will be defined in the claims.

The accompanying drawings illustrate a type-writing machine embodying my improvements, wherein, like letters referring to like parts—

Figure 1 is a plan view of the machine. Fig. 2 is a vertical section from front to rear on the lines X' X' of Fig. 1. Fig. 3 is a detail 30 in plan showing the carriage-bed or guideway and a part of the carriage-frame, ribbon, &c. Fig. 4 and 5 are details, respectively, in section and outside elevation, showing the bearing-flange, type-levers, &c. Fig. 6 is a detail in outside elevation, showing one of the connecting-rods for operating the type-levers from the keys. Fig. 7 is a detail in section, showing the aligning-funnel. Fig. 8 is a detail in horizontal section and plan view, illustrating the feed mechanism for rotating the inking-brush and imparting a longitudinal movement to the ribbon. Fig. 9 is a detail in left end elevation, showing part of the carriage, swinging paper-roll or platen, &c. Fig. 10 is a vertical section on the line X² X² of Fig. 1, showing the line-feed mechanism. Fig. 11 is a bottom view of part of the carriage, showing guide-bands for the paper, &c. Fig. 12 is a detail in cross-section on the line X³ X³ of Fig. 11, some parts being removed. Fig. 13 is a central cross-section through the paper-roll and feed-roll on the line X⁴ X⁴ of

Fig. 11, some parts being broken away. Fig. 14 is a plan view showing the guide-slips for the type-carriers and the means for supporting the same. Fig. 15 is a detail partly in section and partly in elevation, showing the cam-lever used for releasing the feed-dogs from the feed-ratchet automatically on the return of the carriage. Fig. 16 is a detail in sectional elevation of the connecting-rod to the adjustable stop for varying the throw of the flexible or pivoted member of the feed-dog. Fig. 17 is a detail in side elevation of one of the guide-slips for the type-carriers. Fig. 18 is a detail partly in plan and partly in horizontal section, showing part of the manual feed-dog-releasing device.

A bed-plate or casting a, vertical pillars a', an annular head-plate a², and cross-bars a³ a⁴ 70 constitute together the main frame of the machine, which in its main design or outline is similar to that of well-known standard machines.

a⁵ are vertical extensions from the main frame, and a⁶ a horizontal shelf supported thereby and constituting the bed or guideway, upon which rests and travels the paper-carriage and to which are fixed various parts of the mechanism.

b are the key-levers, which are provided with notches b' at their rear ends, held up by springs b² in engagement with a knife-edged fulcrum-bar b³ at the rear end of the bed-plate. This fulcrum-bar b³ is spaced apart a short distance from the body of the bed-plate. This arrangement of the fulcrum-bar b³, notches b' and the upholding-springs b² permits the key-levers to be independently detached and removed from the fulcrum-bar 90 at will by simply depressing the rear ends of the levers against the springs b² and at the same time forcing the levers forward. At their forward ends the key-levers underlie the cross-bar a³ and are provided with finger-pieces b⁴, the stems of which work through a stepped guide-board b⁵. These finger-pieces are provided with character-marks in the customary way. There is a separate character-key for all the type employed in the machine. All the character-keys, as well as the space-bar B, overlie a common cross-bar c', carried by pivoted feed-bail c, having two upwardly and rearwardly extended arms c², which over-

lie a cross-bar c^3 on a vertically-movable feed-plunger c^4 , subject to the action of the keys and the said feed-bail in one direction and to a strong retracting-spring c^5 in the other. 5 The feed-plunger c^4 works through a lower end guide, c^6 , fixed to the rear cross-bar, a^4 , of the frame and through an elongated slot c^7 in the rear flange of the annular head-plate a^2 , the said slot c^7 permitting to the upper end 10 of the feed-plunger a limited swinging movement from front to rear, the same being normally held to the front limit of the said slot by a strong spring c^8 on the top of the head-plate a^2 , the tension of which is adjustable by 15 an eccentric lever c^9 . At its upper end the feed-plunger c^4 carries a pair of escapement-dogs c^{10} and c^{11} , of which the former is the fixed and the latter the flexible or pivoted member and subject to the action of a light 20 spring c^{12} . The feed-dogs c^{10} and c^{11} engage with the feed-ratchet c^{13} on one of the rear cross-bars of the carriage for imparting the letter-feed movements thereto under the action of the feed-plunger c^4 . The pivoted or 25 flexible dog c^{11} works through a keeper c^{14} , carried by the rigid dog c^{10} , and the throw of the same, under the action of its spring c^{12} , is limited by an adjustable stop c^{15} , held and guided on the top of the head-plate a^2 by a slot-and-pin engagement therewith, as shown at c^{16} . 30 The stem of this stop c^{15} is connected to a bell-crank c^{17} , pivoted at its angle to the head-plate a^2 , and provided with a pull-rod c^{18} , extended forward to within reach of the operator 35 of the keyboard and provided with notches c^{19} , engageable with a fixed keeper c^{20} at the front right-hand corner of the cap-plate to hold the said feed-stop c^{15} in any desired adjustment. The stop c^{15} may therefore be set to permit 40 the feed-dogs to take one or more of the teeth of the feed-ratchet c^{13} at every escapement movement, according to the spacing desired. The further connections from the feed mechanism and the action of the same will be described later on. 45

d^2 are the type-bars, and d d' the carriers for the same, of which parts d is the body portion composed of a straight rod, and d' is an enlarged head on the same, which carries 50 the type on its tip or extreme upper end, and is set at an angle to the rod d or body portion of the carrier. The head portions d' of the carriers are larger in cross-section than the type-bars d^2 , and made tapering, thereby serving 55 to protect the type and taking all the wear and tear from the aligning action on the carrier-heads and making it impossible for the type-face becoming battered by an accidental collision of the carriers, as the taper would 60 cause them to glance off. This arrangement also prevents any locking or hooking of the type-bars, as is the case with other lever arrangement.

The type-carriers d d' are suspended and 65 operated by radially-swinging levers d^3 , pivotally attached to the carriers at a point intermediate of their extremities and near the cen-

ter of the same. The levers d^3 are provided at their upper ends with lateral bearing-lugs d^4 , (see Figs. 2, 4 and 5,) which engage with hook-like lug-seats d^5 , turned up from a notched annular bearing-flange d^6 , which is secured to the lower inner margin of the annular cap-plate a^2 . An annular locking-band 70 d^7 works on the rear vertical face of the bearing-flange d^6 above the lug-seats d^5 and has a slot-and-pin engagement with said bearing-flange, as shown at d^8 in Fig. 5, the slot of which is cut at an angle to the plane of the ring's movement. This construction will 75 cause the locking-band d^7 to rise or lower on the flange d^6 when turned thereon. Hence the said band serves as a convenient common lock for securing all of the levers d^3 from displacement when in their working positions on 80 the lug-seats d^5 , while, at the same time, it may be readily raised, so as to permit the levers to be removed from the bearing-flange d^6 .

The type-levers d^3 are adjustably united by eye-screws d^9 with the upper end or forked section of the key-lever-connecting rods b^6 b^7 b^8 , of which parts b^6 is a rigid rod made fast to the key-levers, b^7 is a buckle, and b^8 is a two-pronged or forked upper end section, one member of which carries a pivot-stud b^{10} for 90 engagement with the eye-screws d^9 and the other member of which is engageable with the free end of the pivot and disengageable therefrom by a yielding or spring action, as shown in Figs. 4 and 6. This special feature of 95 construction permits the key-connecting rods to be readily disengaged from the carrier-swinging levers d^3 . The eye-screws d^9 afford a 100 convenient means for adjusting the throw or radial movement of the type-swinging levers d^3 . 105

The type-carriers d d' are in circular arrangement within the annular head-plate a^2 and normally rest with their heads d against an annular buffer d^{10} , composed of leather or other similar stiff yielding material secured 110 to the inner upper corner of the annular head-plate a^2 .

By a radial and endwise movement the type-carriers d d' are thrown to a common point of impression in the axial line of the circle 115 through a bell-mouthing aligning block or funnel f , placed mouth downward and secured rigidly to the bed a^6 , over which the paper-carriage moves. The aligning-funnel f is preferably provided with a removable bushing f' , to take the wear and tear from the carrier-heads d , which bushing, as shown, is removably secured to the upper end of the funnel by a set-screw f^2 . The curve of the mouth 120 of the funnel corresponds to the curve of the 125 type-carriers in passing to the printing-point.

The type-carriers d d' work between radially-arranged horizontal guide-slips g , which are composed of comparatively-light but stiff or unyielding material and are loosely seated 130 in an annular groove g' on the inner face of the annular head-plate a^2 at their outer end, and are provided at their inner ends with notches g^2 , which overhang the vertical flange

of a cup-shaped bearing-head g^3 carried on the upper end of a vertical standard $g^4 g^5$, rising from the bed-plate in the axial line of the aligning-funnel f or type-carrier circle. At 5 their outer ends the guide-slips g are flattened, so as to substantially fill the groove or seat g' in which they are held and properly space the same apart to give clearance for the type-carriers. The guide-slips converge toward the 10 bearing-cup g^3 , on the vertical flange of which their inner ends rest in close contact with each other, but loosely seated, so as to be free to spread laterally under the radial movement of the type-carriers. This arrangement of 15 the guide-slips g permits the same to be converged at their inner ends to a comparatively-small circle, while insuring freedom for the radial movement of the carriers and preventing either the binding of the carriers between 20 the guide-slips or the interference of the carriers with each other in passing and when falling back to their normal position. If desired, for example, the inner ends of the guide-slips 25 g may be made to so fully fill up the flange of the bearing-cup g^3 as to give only lateral spread enough for the entrance of one carrier, in which event two carriers could never come near enough to strike or interfere with each other. The guide-slips should be sufficiently 30 stiff so as not to bend or yield laterally under the action of the carriers.

g^6 is a removable lock flange or collar fitting over the top of the standard g^4 , with its flange overhanging the inner ends of the guide-slips 35 and preventing their removal from the bearing-cup g^3 without the removal of the said lock-collar and its jam-nut g^7 .

The lower or tail ends of the carriers d d' work through guide-passages g^8 of an annular 40 guide or disk g^9 , fixed to the standard $g^4 g^5$ and serving to hold the type-carriers at that point at a fixed distance from the standard or axial line of the circle, while permitting a free endwise movement to the carriers, under 45 the action of the keys and the type-swinging levers d^3 . This annular guide g^9 is preferably composed of leather or other similar stiff yielding material, as this gives the best bearing for the carriers in the action to which they 50 are constrained by this tail-end guide.

As a convenient construction for securing the leather disk g^9 in position, the standard $g^4 g^5$ is composed of two sections, having expanded disk-like clamping-surfaces g^{10} , between which the leather disk d^3 is held, and the lower member of which is provided with a screw-threaded extension g^{11} , engaging a screw-threaded socket g^{12} on the upper section g^4 and working through a perforation in 60 the leather disk.

With the parts so far described it is obvious that under the action of the keys the type-carriers will be directly thrown by a continuous radial and endwise movement to the common point of impression through the aligning-funnel f , and that letter-feed movements 65 will be imparted to the feed-plunger c^4 and

the escapement feed-dogs carried thereby and working with a vertical action on the horizontal feed-rack c^{13} .

70

It will be noted that the type-heads d' of the type-carriers d d' are formed with a taper, diverging upward from the stem portions d and blending into the enlarged type-heads d' . This is a desirable construction, inasmuch as 75 it prevents the interlocking of the carriers in case of engagement and protects the type from being mutilated or defaced.

Turning now to the paper-carriage and its connected parts, h represents the longitudinal bottom bars or runners, and h' the end cross bars or plates constituting together the main frame of the carriage. The runner-bars h ride on horizontal rollers h^2 journaled in the carriage guide-bed a^6 , and are prevented from lateral displacement by vertical 80 guide-flanges a^7 , rising from the guide-bed and engaging with the outer vertical surfaces of the runner-bars h . The carriage-frame is provided with a longitudinal banking-bar h^3 , 85 which, as shown, is at the rear of the frame and carries on its under surface the letter-feed ratchet c^{13} . This banking-bar h^3 has a straight edge which engages with a banking projection, which, as shown, is in the form of 90 a roller h^4 in line with the impression-point crosswise of the carriage guide bed or ways. The banking-roller h^4 , regarded relative to 95 crosswise movement of the carriage on its guide-bed, is fixed, and hence under the forward tension on the said carriage from the spring c^8 applied to hold the top of the feed-plunger c^4 in its extreme forward position the said aligning-bar h^3 will be made to hug 100 the banking-roller h^4 at a point in line with the point of impression, thereby insuring the accurate centering of the paper-roll or platen with the aligning-aperture of the aligning-funnel f , preserving alignment of work regardless of play in the carriage. For convenience, with respect to the removal of the carriage, the said banking-roller h^4 is not 105 journaled in a fixed bearing, but is carried by a pivoted or lever-like bearing h^5 , (see Fig. 3,) which is held normally against a fixed 110 stop-pin h^6 by a strong spring h^7 of so much greater strength than the spring c^8 , applied to force the top of the feed-plunger c^4 forward and the carriage crosswise of its bed in a forward direction, as to render the said roller 115 rigid against the strain from the spring c^8 , as hitherto stated, while at the same time the said roller may be sprung forward to permit the removal of the carriage from its bed. The front carriage-runner is held down to the bed 120 by a spring-clip h^8 , which may be turned forward against the tension of its spring h^9 , so as to disengage the carriage at the front of the frame when it is desired to remove the same.

The carriage is under tension to move toward the left from a driving-spring k , made fast to the head-plate a^2 at one end and applied at its other end, through a cord or wire k' , to a strap-drum spool k^2 set in a vertical 125 130

position and provided with an eccentric strap-drum k^3 connected by a strap k^4 to a hook k^5 , as shown, fixed to the right end of the carriage-frame. The upper end bearing for the 5 spool-shaft k^2 is given by a yoke-shaped bracket k^6 rising from the head-plate a^2 . Under the strain from the spring k the carriage will be fed toward the left, as permitted by the escapement-dogs c^{10} and c^{11} under the 10 action of the feed-plunger c^4 and the key-levers to effect the letter-feed.

It should be noted in respect to the action of the feed-dog c^{10} , which is the rigid or locking member in engagement with the feed-ratchet c^{13} when the feed-plunger is in its 15 lowermost position and the type-carrier at the point of impression, that it is inclined or provided with a cam-surface c^{21} on its forward or engaging edge, which by its camming action 20 assists the spring c^7 in aligning and locking the paper-roll or platen at the point of impression when the impression of the type is being made under the action of the key.

In virtue of the banking-roller h^4 , banking-bar h^3 , and the co-operative parts just hereinbefore described, the carriage may be permitted to work loosely on its guide-bed a^6 between the retaining guide-flanges a^7 and yet be perfectly centered or aligned at the printing-point. This gives a free and easy feed to 25 the carriage and does not require any nice fittings of the carriage-runners and guideways, and permits the use of platen and carriage nearly the full width of the machine.

30 The paper-roll or platen p is journaled in hangers p' , which, as shown, are of segmental form, pivoted to the end plates h' of the carriage-frame. This permits the paper-roll or platen to be swung forward and upward for 35 inspection of the work. A bell-crank rocker or hand-lever p^2 is pivoted to the left-hand forward corner of the carriage and connected by a link p^3 with the left end hanger, p' , and is subject to the action of a spring p^4 tending 40 to hold the said lever and the paper-roll or platen p in its normal position with the link p^3 abutting at its rear end against the fixed stop p^5 rising from the carriage-frame. The 45 handle of the rocker or bell-crank p^2 projects 50 toward the front within easy reach of the operator, for operation by the left hand to throw up the paper-roll and expose the work. This swinging paper-roll would be a convenience on any machine, but is especially desirable 55 on this machine, inasmuch as the carriage-frame does not have a pivotal motion.

At its right end the paper-roll is provided with an annular ratchet p^6 , engaged by a 60 spring-retaining pawl p^7 and a driving-pawl p^8 , pivoted to the upper end of a pivoted lever p^9 , extending outward and pivoted to a corresponding projection p^{10} from the right-hand plate of the carriage-frame, as shown at p^{11} . The lever p^9 carries a flat spring p^{12} , over- 65 arching the pivot p^{11} and bearing at its upper and free end on the driving-pawl p^8 and serving both to hold the driving-pawl p^8 in en-

gagement with the annular ratchet p^6 and to throw the lever p^9 , with the pawl p^8 , downward at its upper end to give the feed-stroke 70 for the pawl p^8 . The upward throw of the pawl p^8 may be limited by a turn-button stop p^{13} , having two or more stop surfaces or steps for single or double spacing, as may be required. The line-spacing lever p^9 , with its 75 co-operating rigid arm p^{10} , projects forward from the right end of the carriage to within reach of the operator's right hand, so that the carriage may be returned to the right end of its runway and the line-feed be effected at 80 the same time by grasping the levers p^9 and p^{10} with one hand.

The feed-roll p^{14} is journaled in hangers p^{15} , pivoted back of the paper-roll to the paper-roll hangers p' , as shown at p^{16} . The feed-roll hangers p^{15} are connected by a common bar p^{17} , which is subject to the crank end of a rock-shaft p^{18} , journaled in the rear cross-bar, p^{19} , connecting the paper-roll hangers p' , and provided on its upper end with a hand-lever p^{20} . The crank-ended rock-shaft p^{18} 90 serves as an adjustable stop for varying the tension on the feed-roll p^{14} through the bar p^{17} , thus giving a yielding pressure on the paper and when thrown back admits of an 95 easy removal of the paper.

p^{21} is the paper-shelf or feed-board carried by the hangers p^{15} .

p^{22} are spring guide-bands for the paper, secured to and adjustable on a longitudinal 100 guide-rod p^{23} , located directly below the feed-roll and having its ends made fast to the hangers p' . The spring-bands p^{22} have rearward projections which underlie the feed-roll, and their free ends extend forward and upward and are bent into a loop to increase their 105 flexibility or yielding action, and the out-turned tips of the same rest and ride upon the front cross-bar, p^{24} , connecting the paper-roll hangers p' . These spring guide-bands p^{22} , 110 it will thus be seen, co-operate with the paper-shelf and feed-roll to form continuous yielding guides for holding the paper to the paper-roll or platen throughout its entire 115 travel, from the point of entrance to the point of delivery, and admits of the use any size of paper.

An envelope-clip p^{25} is pivoted to a central projection p^{26} on the front cross-bar, p^{24} , and held under spring-tension by a spring-finger 120 p^{27} for use either alone or in co-operation with either or both of the intermediate paper-guide bands p^{22} to hold envelopes or narrow paper. The finger may be thrown back while paper 125 is inserted.

The ribbon r is mounted on spools r' at the opposite ends and below the carriage guide-bed a^6 , and passing up through slots r^2 therein and moving longitudinally over the top of the aligning-funnel f and under the platen at the 130 point of impression. For imparting the longitudinal feed to the ribbon r one of the spools r' , the left member as shown, is provided with an extended shaft r^3 , journaled at its forward

- end in the bracket-arm r^4 and provided with a ratchet-wheel r^5 , engaged by a retaining-pawl r^6 and by a feed-pawl r^7 . The feed-pawl r^7 is carried on the forward end of a pivoted cam-lever r^8 , pivoted, as shown at r^9 , to the left end of the head-plate a^2 under the carriage-guideway a^6 (see Figs. 1 and 8) and subject to the action of a cam r^{10} carried on the drum-shaft k^2 under the strap-drum k^3 , and also subject to the action of a spring r^{11} , working in opposition to the cam r^{10} . By these connections the cam-lever r^8 , under the movement of the spool k^2 and the cam r^{10} , simultaneous with the movement of the carriage, will be given a vibratory movement by the cam r^{10} in co-operation with the spring r^{11} , thereby operating the ratchet r^4 and feeding forward the ribbon r with a slow movement in a longitudinal direction, one feed movement of the ribbon being made at every complete trip of the carriage. The ribbon is also given a lateral feed. For this purpose the ribbon passes through a keeper r^{12} , which rests on the guide-bed a^6 and is provided with a slot r^{13} directly over the aperture of the aligning-funnel f . This keeper r^{12} is normally held by a spring r^{14} thrown forward, so that a projection r^{15} thereon rides against the inner vertical face of a horizontal cam-plate r^{16} , fixed to the front member of the carriage-runners h and provided with zigzag inclined surface r^{17} , which under the movement of the carriage in co-operation with the spring r^{14} will throw the keeper r^{12} and the ribbon r successively toward the rear and toward the front across the point of impression, thus giving to the ribbon a lateral feed, as stated. The keeper r^{12} is provided with a shifting-rod r^{18} , by which the same may be thrown back into an idle or inoperative position, together with the ribbon held thereby, and be secured in this idle position by a pivoted button r^{19} , engaging with the front end of the shifting-rod r^{18} . This is a convenience when it is desired for any reason to expose the tip of the aligning-funnel or a type-carrier held up therein and when it is desired to employ direct-printing devices without the use of the ribbon. For this purpose of direct printing I provide an annular inking-brush t , supplied by an automatic ink-feed and located in the path of the type-carriers as they are moved toward and from the point of impression.
- In my preferred arrangement I carry the brush t on the under surface of an annular disk t' , which turns on the lower projecting end of the funnel f , as a pivot, and is removably upheld by pivoted crank-arm hangers t^2 , projecting downward from the carriage guide-bed a^6 , the crank ends of which may be made to underlie the said disk and hold the same up in working position. The top surface of the disk t' is provided with annular recesses t^3 , having feed-ducts t^4 leading to the top of the brush t , which annular grooves or recesses are filled with some suitable absorbent material t^5 for holding the ink and giving the proper feed. An annular shield or cover t^6 is placed over the top of the disk t' to hold the absorbent material in position and exclude the dust.
- The disk t' is provided with an annular ratchet t^7 , which is engaged by a spring-held pawl t^8 carried by the ribbon-feeding cam-lever r^8 . By these connections t^7 and t^8 to the said cam-lever r^8 , operated as heretofore described under the movement of the carriage, the inking-brush t will be kept constantly rotating with a very slow movement, thus insuring an even usage of all parts of the brush on the type, under the movement of the carriers. It is possible to use these direct-inking devices, together with the ribbon, and when so used it will keep the ribbon supplied with ink. The ribbon may, if so desired, be set out of working position. I also provide a type-cleaning brush w , which is of annular form and is secured to the under surface of the hood-flange a^8 , which is secured to the head-plate a^2 and overarches the buffer-ring d^{10} . This locates the cleaning-brush w in the path of the type in their movement to and from the impression-point, and will keep the same clean of all dust and other easily-removed matter.
- With a view of giving better control of the carriage I provide a manual feed-dog-releasing device, consisting of a pivoted lever z , carried by a post z' depending from the rear flange of the head-plate a^2 , one end of which is slotted, as shown at z^2 , and engages with the feed-plunger c^4 , and the other end of which lever is connected by a rod z^3 with a bell-crank z^4 , pivoted to the left-hand front pillar, a' , of the frame directly above the keyboard and provided with a laterally extended or expanded hand-rest z^5 . The bell-crank z^4 is also connected by a link z^6 to a spring-lever z^7 , projecting from the head-plate and provided with the finger-rest or handle z^8 . Under the action of the spring-lever z^7 the bell-crank z^4 will be held up at its forward end and the lever z will either have no action on the feed-plunger c^4 or will tend to assist in holding the same, together with the feed-dogs carried thereby, in their forward or engaging position; but by pressing down, either on the hand-rest z^5 or the finger-rest z^8 , the left end of the lever z will be drawn toward the front and the right end of the same will be thrown toward the rear, thereby forcing backward the top of the feed-plunger c^4 and throwing the escapement feed-dogs $c^{10} c^{11}$ out of engagement with the feed-ratchet c^{13} . This enables the operator to move the carriage backward or forward at will independently of the feed-dogs.
- I also provide an automatic releasing device for rendering the feed-dogs inoperative on the feed-ratchet c^{13} during the return movement of the carriage. For this purpose I provide a cam-bar z^9 on the carriage-frame directly above the banking-bar h^3 , with which engages a cam-lever z^{10} , having a longitudinal

slot z^{11} , through which by set-screw z^{12} it is pivoted to a bracket-arm z^{13} , projecting from the rear flange, a^7 , of the carriage guide-bed a^6 . The rear end of the cam-lever z^{10} is in position to operate directly or indirectly on the feed-dogs to throw the same toward the rear. As shown, the rigid dog c^{10} is provided with a lateral projection z^{14} , against which the rear end of the cam-lever bears. The cam-lever z^{10} carries a spring-finger z^{15} , which engages a releasing-ratchet z^{16} fixed to the cam-bar z^9 . On the forward or letter-feed movement of the carriage the said pawl z^{15} will slip over the ratchet z^{16} , but the instant that the carriage is reversed the pawl will be caught by the ratchet and the lever z^{10} will be rocked and at the same time thrown toward the rear, thereby forcing the feed-dogs out of engagement with the feed-ratchet c^{13} . The cam-bar z^9 and the ratchet z^{16} are cut away near the left end of the carriage-frame, so as to leave a clearance-space z^{17} , into which the pawl z^{15} and the front end of the lever z^{10} may fall when the carriage is at the extreme right of its runway, thereby permitting the feed-dogs to assume their active position in engagement with the feed-ratchet c^{13} .

The general operation of the machine is similar to that of the ordinary standard type-writers, the nature of which action is so well known and is so obvious from the preceding description that a repetition or summary statement of the same is not deemed necessary for the purposes of this case. The actions and advantages of my improvements in the details of the mechanism have been stated in connection with the specification and detailed description of the respective parts. It may be noted in a general way, however, that the machine is comparatively easy to make, is light of touch, quick in action, accurate in alignment, and distinct in impression.

What I claim, and desire to secure by Letters Patent of the United States, is as follows:

1. In a type-writing or similar machine, the combination with radially-movable type-carriers, of a corresponding series of radial guide-slips, between which the carriers work, loosely seated with freedom for lateral or spreading movement at their inner ends, under the radial motion of the carriers, substantially as and for the purposes set forth.

2. In a type-writing or similar machine, the combination with the central aligning-funnel, the radial guide-slips and the radial and endwise-movable type-carriers, of a common central support for the inner ends of said guide-slips, on which the same are free to move or spread laterally, and a common central guide-disk with guide-passages, for holding and permitting an endwise movement to the tail end of the carrier, substantially as described.

3. In a type-writing or similar machine, the combination with the annular head-plate or basket-rim a^2 , of the aligning-funnel f , the central standard g^4 g^5 , the cup-shaped bearing-head g^3 , the radial guide-slips g , loosely seated

in the groove g' of the rim a^2 , and provided with notches g^2 , at their inner ends loosely engaging the flange of the cup g^3 , the guide-disk g^3 with the guide-passages g^8 , the key-operated levers d^3 suspending the carriers d d' with their upper ends working between the said guide-slips and the lower ends in said guide-disks, substantially as and for the purposes set forth.

4. The combination with the rim a^2 , having the groove g' , of the guide-slips g , the standard g^4 g^5 , the cup-shaped bearing-head g^3 engaged by the notches g^2 , at the inner ends of the said guide-slips, and the locking-collar g^6 , for holding the guide-slips to the bearing g^3 , substantially as described.

5. In a type-writing or similar machine, the combination with the carrier-operating levers d^3 , having the lateral bearing-lugs d^4 , of the bearing-plate d^6 , having the bearing-lug seats d^5 , and the locking-ring d^7 working on the plate d^6 , and having the slot-and-pin connection d^8 with the said plate, substantially as and for the purpose set forth.

6. The combination with the paper-carriage, of the paper-roll p , journaled in the hangers p' , pivoted to the carriage-frame, of the bell-crank or rocker lever p^2 , the link p^3 connecting the same with one of the hangers p' , and subject to the action of the spring p^4 and limited by a fixed stop p^5 , substantially as described.

7. The combination with the cross-bar p^{19} , connecting the hangers p' , in which is journaled the paper-roll p , of the feed-roll p^{14} , journaled in the hangers p^{15} , pivoted to the hangers p' , and connected by the spring-bar p^{17} , of the crank-ended rock-shaft p^{18} , journaled in the bar p^{19} , bearing with its crank end against the spring-bar p^{17} , and provided with the hand-lever p^{20} , substantially as described.

8. In a type-writing or similar machine, the combination with the bed or guideway for the carriage, of a banking-roller located laterally in line with the impression-point and rigid against lateral motion under the strain of the carriage, of the paper-carriage under strain to move crosswise of its guideways, and provided with a banking-bar hugging said roller, substantially as and for the purpose set forth.

9. In a type-writing or similar machine, the combination with the carriage guide-bed, of the banking projection, located laterally in line with the impression-point crosswise of said bed, the carriage having the banking-bar with straight edge engaging said projection, the feed-ratchet on said carriage-frame and the escapement feed-dogs engaging said ratchet and under tension to force the carriage crosswise of its guideway, substantially as and for the purposes set forth.

10. In a type-writing or similar machine, the combination with the carriage guide-bed, of the banking-roller, rigid against lateral movement under the lateral strain on the carriage, the paper-carriage having the banking-bar engaging said roller, the feed-ratchet

on the carriage-frame, the vertically-movable feed-plunger with feed-dogs engaging said ratchet and free for a tilting movement at its upper end and under tension to swing forward, one member of which feed-dogs has an inclined or cam surface engaging said ratchet, the key-levers under spring-tension and the feed-bail c^4 and retracting-spring c^5 applied to said plunger, all the said parts operating substantially as described.

11. The combination with the paper-carriage, under tension, to move laterally across its guideways and having the longitudinal banking-bar h^3 , of the banking-roller h^4 carried by the pivoted lever h^5 , and held against the fixed stop h^6 , by a spring h^7 , of greater power than the lateral tension on the paper-carriage, substantially as and for the purposes set forth.

12. The combination with the paper-carriage, guideway a^6 , having the retaining guide-flanges a^7 , of the paper-carriage frame having the runner-bars h retained by said flanges, the banking-bar h^3 engaged by the pivoted and forwardly-yielding banking-roller h^4 , and the spring-clip h^8 engaging over the front runner of the carriage and adapted to be turned out of engagement therewith, for the removal of the carriage from the guide-bed, substantially as described.

13. In a type-writing or similar machine, the combination, with the paper-roll or platen p , provided with the annular ratchet p^6 , of the retaining-pawl p^7 , the line-feed pawl p^8 , engaging said ratchet, the fixed handle p^9 , projecting from the carriage-frame, the lever p^9 pivoted to the handle p^9 , and provided with the spring p^{12} bearing on the end of the pawl p^8 , the said parts operating substantially as described, to effect the line-feed.

14. The combination with the paper-roll p and the feed-roll p^{14} , of the guide-rod p^{23} and cross-bar p^{24} , connecting the hangers, which carry the paper-roll, and the adjustable spring p^{22} , adjustable on the rod p^{23} and the bar p^{24} , substantially as described.

15. In a type-writing or similar machine, the combination with the paper-roll or platen journaled in hangers pivoted to the carriage-frame, of the front bar p^{24} connecting said hangers, the envelope-clip p^{25} pivoted to a central projection p^{26} fixed to said bar and the spring-finger p^{27} , bearing against the clip, substantially as described.

16. The combination with the feed-dogs c^{10} and c^{11} engaging the feed-ratchet c^{18} of the paper-carriage, of the adjustable stop c^{15} , the bell-crank c^{17} , notched rod c^{18} and keeper c^{20} , substantially as and for the purpose set forth.

17. In a type-writing or similar machine, the combination with the carriage having the feed-ratchet c^{18} , of the feed-dogs c^{10} and c^{11} engaging said ratchet, one of which is provided with the projections c^{14} , of the cam-bar z^9 on the carriage-frame, and the slotted cam-lever z^{10} engaging with said cam-bar at its forward end and with said projection at its

rear end, adapted to disengage the feed-dogs on the return movement of the carriage, substantially as described.

18. The combination with the feed-ratchet c^{18} , of the feed-plunger c^4 free for pivotal movement at its upper end, and provided with the escapement feed-dogs c^{10} and c^{11} engaging said ratchet, of the cam-bar z^9 , provided with the releasing-ratchet z^{16} , and the slotted cam-lever z^{10} having the spring-fingers z^{15} engaging said releasing-ratchet, and operating to release the dogs on the return movement of the carriage, substantially as described.

19. The combination with the feed-ratchet and feed-dogs, of the feed-plunger c^4 , the releasing-lever z pivoted to the post z' , and provided with a slot z^2 engaging the plunger c^4 , the rod z^3 , the bell-crank z^4 with expanded hand-rest z^5 , the link z^6 , connecting said bell-crank with the spring-lever z^7 having the finger-rest z^8 , substantially as described.

20. In a type-writing or similar machine, the combination with the carriage under tension, of the escapement-feed for the same, releasable by the keys, and a ribbon-feed, comprising a ratchet applied to one of the ribbon-spools, a spring-held pivoted cam-lever, provided with the feed-pawl engaging said spool-ratchet, and a rotary cam operated simultaneously with the movement of the carriage and co-operating with the cam-lever spring to vibrate said lever and effect the longitudinal feed of the ribbon, substantially as described.

21. In a type-writing or similar machine, the combination with the carriage, of the driving-spring for the same, acting thereon through a strap-drum and strap, the ribbon and ribbon-spools, the cam r^{10} , the cam-lever r^8 , spring r^{11} , ribbon feed-pawl r^7 , ratchet-wheel r^5 , carried by the ribbon-spool shaft r^3 , substantially as described.

22. In a type-writing or similar machine, the combination with the carriage, of a pair of fixed guides, through which the ribbon passes, a keeper-guide embracing said ribbon intermediate of said guides, a spring tending to throw said keeper in one direction, and a zigzag cam-plate carried by said carriage and working against said keeper in opposition to said spring, substantially as described.

23. In a type-writing or similar machine, the combination with the carriage, of the ribbon, between the type and the platen, and an inking-brush in the path of the type, as moved by the carriers, whereby said ribbon may be replenished with ink from said inking-brush, substantially as described.

24. In a type-writing or similar machine, the combination with the carriage under strain, the ribbon and the feed for the same, and an inking-brush in the path of the type, as moved by the carriers, provided with an automatic inking-feed, substantially as and for the purpose set forth.

25. In a type-writing or similar machine, the combination with the carriage under

strain, the ribbon and ribbon-feeding mechanism, of the rotary inking-brush in the path of the type, as moved by the carriers, and a brush-rotating device for keeping the brush in motion and uniformly distributing the ink, substantially as described.

26. In a type-writing or similar machine, the combination with the carriage under tension, of the escapement-feed for the same, releasable by the keys, the inking-ribbon, having one of its spools provided with a ratchet, the rotary inking-brush having a ratchet, a spring-held pivoted cam-lever, a pair of pawls

carried by said lever and engaging one with said ribbon-spool ratchet and the other with 15 said brush-ratchet, and a rotary cam operated by the carriage and operating on said cam-lever to effect the feed of said ribbon and said brush, substantially as described.

In testimony whereof I affix my signature 20 in presence of two witnesses.

FERDINAND WOLTER.

Witnesses:

E. L. SCOVILLE,
E. E. GOODSELL.
